SIGN

Harry A. Husted, St. Joseph, Mich., assignor to
A. T. Tebbe, St. Joseph, Mich.

Application June 11, 1947, Serial No. 753,922

1 Claim. (Cl. 40—125)

1

This invention relates to improvements in signs and particularly to improved reflecting and light diffusing signs, which are especially suitable for use, for example, as automobile license plates, highway markers, warning signals, or the like, and various commercial and advertising signs of general purpose and utility.

A primary object of this invention is for the provision of an improved sign construction which is relatively simple and inexpensive and may be manufactured at comparatively low cost to provide a sign in which the letters, numbers and other characters thereon are clearly discernible and easily distinguishable at considerable distances at night as well as in daylight.

Another object of the invention is to provide such a sign comprising a sheet metal panel or base plate provided with uniform, closely arranged, integrally formed protuberances which strengthen and rigidify the sign and provide reflecting and light diffusing elements defining the sign background or field which sets out and accentuates the numbers, letters, and other characters on the sign with maximum clarity and distinctness.

Such sign characters may comprise any arrangement of numbers, and/or letters together with any selected form of design such as a border or other creation for ornamental or artistic purposes. It is to be understood, accordingly, that any reference in this disclosure to sign characters in general applies to any matter whatsoever which may be carried by a sign in accordance with the present invention regardless of the specific formation thereof or the method by which such characters may be provided on the sign. It is fully contemplated, further, that such sign characters be defined by the shape of the sign itself as, for example, in the case of road signs in the form of curved arrow indicating a curve in the road, or in the form of a cross designating an intersection.

A further object of the invention is to provide a sign of the kind described in which the reflecting and light diffusing protuberances comprising the background of the sign are integrally formed on a polished metal surface to have a high degree of luster and brilliance which presents a sharp contrast to the characters on the sign which are painted or otherwise made non-reflective in any suitable way so that the contrast is at a maximum for most effective legibility.

Another object of the invention is to provide a sign construction such as described in which the sign characters are presented in relief or in

2

raised projecting relation to the field or background of the sign to increase the clarity and visibility of the sign characters.

A further object of the invention is to provide such a sign construction in which the sign characters in any form are outlined by contrasting marginal portions which set out and emphasize the sign characters in sharp distinction to the background of the sign.

Still another object of the invention is to provide various improvements in signs embodying the foregoing features, individually and severally, and the method of making such signs in a minimum number of operations depending on the specific form of the sign characters provided, and which method, in any instance, is admirably suited for the economical quantity production of the signs at comparatively low cost.

Further objects and advantages of the invention and other new and useful features in the construction and arrangement thereof will be readily apparent as the following description proceeds with reference to the accompanying drawings, for purposes of illustration but not of limitation, in which like reference characters designate like parts throughout, and in which:

Figure 1 is a front view of a sign provided in accordance with the invention in the manner of an automobile license plate, or the like, for example;

Figure 2 is a front view on an enlarged scale of a marginal portion of the sign shown in Figure 1;

Figure 3 is an enlarged sectional view of Figure 1 taken on line 3—3 looking in the direction of the arrows; and,

Figure 4 is an enlarged sectional view of Figure 1 taken on line 4—4 looking in the direction of the arrows.

Figures 5, 6 and 7 are sectional views illustrating the several steps in the method of making the sign shown in Figures 1—4 inclusive, with Figure 5 representing the initial step whereby the panel is provided with a surface of bright, lustrous material;

Figure 6 represents the next step in the method whereby the article shown in Figure 5 is provided with painted areas defining the sign characters; and,

Figure 7 discloses the following step in the method whereby the sign is provided with the closely arranged integrally formed protuberances which rigidify the panel and define the background of the sign.

Figure 8 illustrates a sign construction similar

to that of Figures 1-4 inclusive in which the sign characters are raised in relation to the field or background of the sign;

Figure 9 represents another form of raised sign characters which are employed in the improved sign construction; and,

Figure 10 shows a further form of raised sign characters which are provided in a sign in accordance with the invention.

Referring now, more particularly, to the drawings, Figure 1 discloses the invention as embodied in a vehicle license plate, or the like, by way of an example only of one form or application of very many to which the invention may be put, as for instance, highway signs, vehicle warning signs and signals, and commercial and advertising signs of any purpose or nature. The invention comprehends, further, the provision of various sign constructions in accordance with the instant disclosure which are suitable for fastening or attachment to signs already in use as an economical procedure for providing such existing signs with reflective properties and other qualities conforming to a uniform standard or code.

The panel, blank or base plate of the sign, designated generally 10, preferably is of light weight stainless steel but may be of any other suitable sheet metal of sufficiently light gauge to permit ready stamping thereon in providing the sign with the desired reflecting and light diffusing elements in accordance with the invention. The finished panel or plate must be stiff and relatively rigid in most instances and to this end, the integrally formed protuberances or reflecting elements which are stamped thereon, add to the stiffness and rigidity of the panel in a completed sign structure.

The front or outer face of the panel which is exposed to view in a completed sign is provided with a bright, lustrous surface that may be provided in any desired manner as by a coating of luminous paint or by a suitable plating operation. Preferably, the panel 10 is of stainless steel which may be readily and cheaply electroplated to provide the bright lustrous surface on the panel. It is also preferable that chromium plating be employed to provide such a bright lustrous surface and nickel plating also may be used but nickel does not maintain its luster and brilliancy as well as chromium. As represented in Figure 5, the base plate 10 of the sign is plated in its initially flat form to provide the bright, plated surface 12. The use of stainless steel for the base panel 10 is in that it is weather resistant and not subject to corrosion. In any case, the metal plate or blank 10 and the bright surface 12 thereon should be non-corrosive and otherwise weather resistant in order to adapt the sign for exposure without the need for a protective covering to protect the same from weather effects.

After the initial procedure of providing the panel 10 in its flat form with the bright plated surface 12, the sign characters are provided thereon in any suitable manner as by painting or printing the same through the medium of a stencil, silk screen, printing rollers and the like. As previously indicated, the sign characters may comprise any arrangement of numbers and/or letters 15 with or without a border 15' or other creation or design for ornamental or artistic purposes. Figure 6 illustrates this step in method whereby the initially flat blank or panel 10 having the bright lustrous surface 12 is provided with such painted sign characters 15 and the border 15', Figure 1 and 2, or other painted design or ornamental creation.

Figure 7 illustrates the next step in the method whereby the entire blank, panel or base plate 10, provided with the painted sign characters 15 and 15', is subjected to a stamping operation, either by a die press or roller dies, to form the integral protuberances 20 which cover the entire face of the blank or panel, as shown in Figure 1. As illustrated in detail in Figures 2, 3 and 4, the protuberances 20 are generally diamond-shaped, blunt elements which are arranged in uniform geometrical design over the entire area of the blank or panel 10. The diamond shaped elements 20 are of the same size and configuration and are closely arranged together in substantially edge to edge formation in projecting relation to the front face of the blank or panel 10. Accordingly, the front face of the blank is predominated by the said protuberances 20 rather than by the slight adjoining plane areas therebetween. As seen in Figures 1 and 2, the diamond-shaped protuberances 20 are disposed in diagonal parallel rows in edge to edge relation to each other. The protuberances also are arranged in horizontal rows with the elements in each horizontal row in staggered nested, relation to the elements of the immediately adjacent horizontal row of protuberances on either side thereof.

The invention fully contemplates the provision of the protuberances in any similar or equivalent design wherein such elements are relatively blunt and little or no space exists between adjacent protuberances. However, the diamond-shaped design of the protuberances 20, as shown, has been found highly satisfactory and most practical in that the stamping thereof may be readily performed without cracking or breaking the bright, lustrous surface 12 or any of the painted areas such as 15, 15'. To this end, the diamond-shaped protuberance are made relatively shallow in relation to their size but sufficiently deep to provide a well defined curved cross section having its convex contour extending in projecting relation to the outer or front face of the blank or panel. The protuberances 20 otherwise are all stamped rearwardly out of the plane of the front or outer face of the panel 10 to provide a complete surface of closely arranged convex-concave elements which are integrally formed on the front face of the blank.

As stated, the front or outer face of the sign is provided with a bright lustrous surface such as the plating 12 which coats the blank or panel uniformly throughout including each of the protuberances 20 and the slight, narrow areas therebetween. The formation of the protuberances in closely arranged relation serves not only to reinforce and rigidify the metal blank but also provides the outer face thereof with much greater brilliancy and luster than a surface which is merely flat. Because of the outer convex contour of the protuberances 20, any light impinging on each protuberance is reflected as a diffused series of diverging rays and, as a result, the intensity of the reflection and the brilliancy of the reflecting surface is considerably increased. Accordingly, in the areas which are not covered by the painted sign characters such as 15, 15', for example, the exposed protuberances 20 present a bright overall surface 21 by reason of the relatively small size of said protuberances and the close spacing thereof. Such bright surfaces 21 are extremely brilliant when light from any source impinges thereon and for all practical purposes, are as brilliant at night as during the daytime.

It will be understood, accordingly, that the un-

painted bright surfaces 21 outline and clearly define the painted sign characters such as 15, 15' which are relatively dull and nonreflecting, and consequently a sharp contrast is provided. This, of course, sets out the painted sign characters against the background or field defined by the bright surfaces 21 such that the outline of said characters is clear, distinct and easily discernible.

A sign construction in accordance with the foregoing preferably is provided with the painted sign characters 15, 15' applied to the plate or blank in its flat condition as described with reference to Figure 6 inasmuch as the paint may be most easily controlled and precisely applied under such conditions. However, if desired, the sign characters may be applied after the sign plate has been stamped with the protuberances 20 but in this procedure care must be taken to insure application of the paint into the valleys and narrow surfaces between the adjacent protuberances 20 and also, to guard against undesired flowing of the paint beyond the intended design.

Figure 8 illustrates a further form of the improved sign which is generally similar in construction and the method of making the same to that described with reference to Figures 1-7 inclusive. In this embodiment, a further step in the stamping operation is effected to raise the sign characters 25 above the field or background defined by the bright surfaces 21. This serves to make the sign characters even more distinct and outstanding. By reason of the raised relation of the sign characters 25, the painted surfaces 26 thereon may be applied either when the plate is flat as described with reference to Figures 1-7 inclusive, or, after said raised characters have been formed. This latter procedure is readily accomplished by means of a paint wheel or paint roller adapted to brush the top surfaces of said characters to deposit the layer of paint 26 thereon without contacting or marring the bright surfaces 21 forming the field or background of the sign. In a similar relation, the tops of the raised sign characters may be subjected to a polishing wheel to increase the natural luster and brilliance of the plated protuberances 20' to a higher degree than that afforded by the bright surfaces 21 forming the background or field of the sign. In this way, the raised sign characters 25 would have a distinct contrast and an inherent greater brilliancy differing from that of the sign background or field 21.

Figure 9 represents a further embodiment of the invention in which the top surfaces of the raised sign characters 35 have a substantially flat contour and are provided with a coating of paint 36 by means of a paint roller or wheel as described with reference to Figure 8. In addition, flat marginal portions 37 are provided which surround the raised sign characters thus provided, and these flat marginal positions have a painted surface 38 contrasting to the color of the paint 36 on the top of the flat surfaces of the said raised sign characters 35. The flat surfaces on the tops of the raised sign characters 35, and also the flat marginal portions 38 bordering the same may be readily provided for in the same operation by which there are stamped the protuberances 20 defining the bright surfaces 21 of the sign background. The flat surfaces on the tops of the sign characters may be either painted or polished in the same manner and for the same purposes described with reference to the form of the invention shown in Figure 8.

Figure 10 illustrates another form of the inven-

tion in which the raised sign characters 45 are provided in a manner generally similar to that described with reference to Figures 8 and 9, and in which the raised sign characters are outlined by flat marginal portions 47 having painted surfaces 48. The tops of the raised characters 45 may be painted a contrasting color to the painted areas 48 on the flat marginal portions 47 when the plate is in its initially flat condition as described with reference to Figures 1-7 inclusive, or by means of a painting roller or wheel applied to the tops of such raised sign characters after they have been formed. Similarly, the tops of the raised sign characters may be subjected to a polishing wheel to enhance the brilliance of the plated protuberances 20' to contrast sharply against the painted marginal portions 48 and the bright surfaces 21 defined by the plated protuberances 20 forming the background or field of the sign.

While the invention has been described in detail with specific examples, such examples are intended as illustrations only, since it will be apparent to those skilled in the art that other modifications in the construction, arrangement and general combination of parts thereof may be devised without departing from the spirit and scope of the invention. The present embodiments are therefore to be considered in all respects as illustrative and not restrictive, the scope of the invention being indicated by the appended claims rather than by the foregoing description, with all changes falling within the scope, meaning and range of equivalency of the claim intended to be embraced therein.

What is claimed and desired to be secured by United States Letters Patent is:

A sign comprising a metal panel having a bright surface area provided throughout with diamond-shaped protuberances, a painted sign character painted over a part of the diamond-shaped protuberances in said area, whereby the unpainted diamond-shaped protuberances in said area serve as light reflecting elements defining the outline of said painted sign character, said diamond-shaped protuberances being arranged in closely positioned rows with the diamond-shaped protuberances in each row being in staggered and nested relation to those in the adjacent rows, whereby any light striking a face of one of said diamond-shaped protuberances will be reflected against a face of an adjacent diamond-shaped protuberance to provide a brilliant contrast to said painted sign character.
